TELEPHONE-EXCHANGE SYSTEM.

1,107,142.

Specification of Letters Patent.

Patented Aug. 11, 1914.

Application filed December 23, 1905. Serial No. 293,148.

To all whom it may concern:

Be it known that I, EDWARD E. CLEMENT, a citizen of the United States, residing at Washington, in the District of Columbia, have invented certain new and useful Improvements in Telephone-Exchange Systems, of which the following is a specification, reference being had therein to the accompanying drawings.

10 My invention relates to telephone exchange systems, and has for its object the provision of semi-automatic apparatus and circuits for the interconnection of lines, whereby the efficiency of a system may be increased while the cost of its installation and operation may be decreased.

According to the present invention the subscribers' lines do not terminate on spring-jacks, but upon contacts in circular rows or banks of what I shall call primary selector switches. Each of these switches is connected to a spring-jack, and as I may have one switch for every ten lines, the number of answering jacks is thus much less than has heretofore been possible. The operator in answering the call does not communicate with the subscriber, but merely selects an idle plug and inserts it in the jack which has been temporarily appropriated by the calling line. Each plug forms a single cord terminal of a trunk line leading to a first selector automatic switch, which has associated with it second selector and connector switches, so that when the subscriber is once given access to a set of switches, he can at once proceed as usual in automatic systems to connect himself with the wanted line.

My invention is illustrated in the accompanying drawings, in which—

40 Figure 1 is a diagram of a subscriber's station and line, together with the co-operating apparatus and circuits on the manual or answering switchboard. Fig. 1^a is a top plan view of the switching apparatus on the answering switchboard. Fig. 2 is a similar diagram of the trunks or automatic selector and connector switches.

Referring to Fig. 1, the subscriber's station A is provided with apparatus usual in common battery systems, consisting of the transmitter T, receiver R, hook H, condenser C and ringer Q. In addition I provide the low-wound signal magnet Q' controlling the target, which announces the answer to the call and the key K for breaking and making the circuit, both being in series

with the talking set. The line-wires 1 and 2 pass to the contacts *n* and *m'* of the cut-off relay N and thence normally to the wires 5 and 6, leading respectively to the line relay M and to ground. The relay M is connected on the other side by the wire 7 to battery B, which preferably supplies current for all purposes. The local circuit 10 controlled by the line relay M passes through the open contacts of said relay to the battery wire 7 on the one side, and to a bank contact *p* individually associated with the line 1—2 in the primary selector switch P. The connection of wire 10 to the bank contacts may be through a switch by which it can be shifted to any one of several primary selectors P at will, in this way distributing or shifting the load according to the conditions under which the several switches are working. When the cut-off relay N is energized it disconnects the contacts *n*, *n'*, from the line-relay and ground and connects them to the wires 3 and 4 leading to the talking contacts *p'* in the primary selector banks. The pair of talking contacts *p'*, associated with each line, bear a fixed relation to the test contact *p* in each switch.

In the selector switch P the shaft P' is constantly revolving, and I use a revolving arm having a solenoid with a movable core, clutched to the shaft by the inner end of the core *p'* engaging a notch *p*^o and the outer end adapted to engage any one of a succession of openings in a stop or jack ring. This ring *p*^o is concentric with the shaft and has its openings respectively opposite corresponding groups of line and trunk contact springs *p*⁴, *p*⁴, *p*⁵. The springs *p*⁴, *p*⁵ are preferably integral throughout the circle but cut in combs with one pair of individual members opposite each pair of line-contacts *p'*. The solenoid has two windings S¹⁰ and O¹⁰, one of which controls the solenoid when a busy contact is found and the other controls and holds up the solenoid after the operator inserts the answering plug. In other words, as soon as the wiper *p*^o comes upon a charged or busy contact the winding S¹⁰ takes current and pulls in the solenoid core *p'* loosing the arm from the shaft and simultaneously projecting its forward insulated end through the jack ring *p*^o between the springs *p*⁴, *p*⁵, thereby pressing them against the line contacts *p'* of the calling line and stopping the arm. The insertion of this plug in the jack acts just as it would in

a manual system. The relays S^2 and N get current and S pulls up, whereupon the winding O^{10} gets current through the arm p^o and the ring p^o and keeps the solenoid core 5 p^r pulled in. After the plug is inserted by the operator the relay M is disconnected through the pulling up of the armature n of the cut-off relay N and the test contact is 10 free from battery so that no other solenoid with its contacts sweeping over this particular test contact would stop.

The solenoids D and D' , controlled by the relay S' , both respond to the makes and breaks in the subscriber's line while impulses are being sent to operate the automatic switches. The solenoid D holds up its core d^2 so long as the impulses are coming in, but during the interval between each group or set of impulses the core d^2 drops 20 and sends a rotary impulse over one side of the trunk to the automatic switches. The solenoid D' has its core d'^1 drawn up during the sending of the impulses and throughout the time the line is in use. At the end 25 of such a time when the calling subscriber hangs up the core d'^1 drops and connects battery simultaneously to both sides of the trunk, thereby releasing the various switches.

Having thus described the essential features of the apparatus wherein my invention particularly resides, I will now pass to a set of automatic selector switches with which it is intended to work conveniently, translating mere makes and breaks in the metallic 30 circuit of the line into whatever impulses, over whatever branches, are required. These switches are shown diagrammatically in Fig. 2, being designated respectively by the letters F , F' , F^2 , and are of the type 35 shown in Letters Patent No. 815,176 and No. 40 815,321, granted March 13, 1906, to Keith and Erickson. It is unnecessary for me to describe their mechanical connections herein, as they are well understood by all those 45 skilled in the art and the diagram of Fig. 2 will, therefore, be sufficient. The wires 21 and 22 which are broken at the right-hand side of Fig. 1, commence again at the left-hand side of Fig. 2 and pass to switch-arms 50 47 and 48, which normally rest upon contacts forming terminals of the wires 40 and 42, leading respectively to the relay magnets V and R , (which are called the vertical and rotary relays respectively) of the first 55 selector switch F . Impulses coming over the wire 21, when the switch is normal, affect the relay V , passing through its windings to ground, while impulses going over the wire 22 affect the relay R , passing 60 through its windings to ground.

The switch F comprises a rotary spindle f , carrying insulated contact wipers w , w^2 , which are adapted to sweep over the set of contacts w' and w^3 , constituting the termi-

nals of trunk conductors 210 and 220 passing to second selector switches. The spindle f also carries an insulated test and releases wiper w^o , which sweeps over a set of contacts w^{10} , corresponding to the contacts of the talking circuits w' and w^3 , but forming 70 the terminals of test and release circuits 60 for the second selector switches. The vertical relay V controls a magnet V' called the vertical magnet, which is provided with a ratchet mechanism to step the spindle f up 75 to the desired row of contacts w' , w^3 , w^{10} , these contacts being arranged in horizontal rows of ten each. The rotary relay R controls what is called the rotary magnet R' , which is fitted with a ratchet mechanism by 80 which it can turn the spindle f , one step at a time, making its wipers rest upon one set of contacts after another in the respective rows selected. The magnet R' is automatic in its operation, that is to say it carries an 85 insulating wedge on its armature, shown at r' , which acts to make and break its own circuit as it vibrates. The armature also carries a projecting lug or stud, r^{10} , which in operation impinges against the armature 90 t of the magnet T^o , whose function will appear in the statement of operation.

U is the release magnet, equipped with an armature lever, which upon being attracted 95 will lift the retaining pawls off the ratchets of the spindle f , permitting the latter to be turned back to zero and dropped to its normal position by a suitable spring.

T is the test and release relay, connected on the one side to the switch-arm 49 and 100 on the other side by wire 50 to the wiper w^o . In testing, the arm 49 is on the middle contact, connecting the relay T back through wire 52 to the spring-contact r of the rotary relay R , which at the moment of testing is 105 energized so as to render the relay T at that moment active.

The switch-arms 46, 47, 48 and 49 are mounted as a unit and moved together, one step at a time, being all set back into the 110 position shown in the drawing when the magnet U restores the switch to its zero or inactive position, and being thence released step by step by means of an escapement carried by the armature t of the relay T^o . 115

The second selector switch F' , and its circuits, are identical in all essential particulars with the first selector and its circuits. The vertical and rotary relays in this switch are marked V^2 and R^2 , the vertical and 120 rotary magnets are marked V^3 and R^3 , the private or controlling relay is T^2 , the test and release relay is T^7 , and the release magnet is U' . The switch wipers are marked w^4 , w^6 , w^{40} , while the trunk terminals for the connector groups are marked w^5 , w^7 , and w^{50} . The circuits bear the same numbers as their corresponding wires in the first selec-

tor, each with a naught added. Thus, the trunk-wires are 210 and 220, the side switch-arms are 460, 470, 480 and 490, etc.

It will be observed that the vertical and 5 rotary relays and magnets are cut off in the last step of the side switch-arms heretofore described, leaving a clean talking circuit. In the connector switch F^2 , to which we now 10 come, this is not so. The vertical and rotary relays V^4 and R^4 are both intended to work the switch spindle step by step, and serve during connection to afford control over all the switches in the series, working through the back release wires and the relays T , T' , 15 etc. From its multiples in the banks of the second selector switches, the wire 61 comes into the connector switch and terminates at a condenser C' , while the wire 62 terminates at a similar condenser. From 61 a branch 20 extends to the relay V^4 , which is grounded on the other side. From 62 a branch 64 extends to the relay R^4 , which is grounded likewise on the other side, both these 25 branches being permanent. The vertical relay V^4 controls a local circuit 78, passing from the spring v to a pair of contacts on the relay T^3 to the switch-arm 67. Remembering that the arms 67, 68, 69 and 70 all move together as controlled by the escapement of 30 the magnet T^3 , the normal position of arm 67 puts the wire 78 into connection with the wire 80, thence to the vertical magnet V^5 , which raises the spindle f step by step to select the desired row of line-contacts; and 35 this magnet is connected to battery by the wire 74. With the switch-arm 67 in the second position, the wire 78 is put into connection with the wire 79 and thence with the rotary magnet R^5 , fitted to turn the spindle f 40 step by step, not after the fashion of the selector rotary magnets, R' , R^3 , but only as energized for each step separately. Thus, the spindle may be turned around to a particular contact in the selected row. With 45 the switch-arm 67 in its third position the wire 78 is connected to the wire 81 and so to the ringing relay Z , which controls the contacts z , z' , z^2 , z^3 , z^4 and z^5 , these contacts being included in the two sides 65 and 66 of 50 the talking circuit wires, terminating on the switch-arms 68 and 69, open during selection, but at the last stage, when the subscriber wanted is actually connected, closed to the wires 71 and 72 leading to the talking 55 circuit wipers w^8 and w^9 . When the magnet Z is energized it works its contacts just as an ordinary manual ringing key does, breaking the conductors 65 and 66, and connecting the forward end to the generator G .

60 U^2 is the release and test magnet, X , X' are bridged battery or retardation coils in the battery supply circuit to the called line. The functions of these and other parts will appear further from the statement of operation. It will now be possible to comprehend

the operation of my invention as embodied in the apparatus illustrated in Figs. 1 and 2.

I have not shown the substation and line of the subscriber to be called, but these are supposed to be the same as the substation A 70 and line 1-2. We will assume the subscriber A to be calling. He takes his receiver from the hook, closing the line-circuit through his talking set as follows: B, 7, M, 5, n , 1, K, switch-hook, talking set, Q' , 2, n' , 75 6 and ground back to battery. The relay M becoming energized pulls up its armature and closes a circuit from battery to the contacts p^25 in the primary selector banks, as follows: B, 7, 8, 9, 10, p^25 . The contacts p^25 80 thus having their potentials raised, when any one of them is touched by the wiper p^3 of a primary selector switch in its revolution, the circuit through the winding S^{10} of the solenoid is completed to ground. The solenoid 85 thereupon pulls up its core and the insulated portion P^{10} enters the jack springs p^4 and p^5 , making connection with the line springs p' . As soon as this action takes place the trunk-wires 15 and 16 are connected respectively to the wires 3 and 4, which places the relay S^2 in series with the cut-off relay N by the following path: battery B, 110, S^2 , 104, j^4 , j' , 16, p^5 , p' , 4, N to ground. The relay N 90 becoming energized disconnects the line relay 95 M and connects the line wires 1 and 2 to the trunk-wires 15 and 16, respectively. The relay M being disconnected frees the test contact p from battery and the circuit of the winding S^{10} of the solenoid is opened, but 100 the circuit of the winding O^{10} is completed by the following path: battery B, 110, 102, the contacts of the relay S , since this relay becomes energized as soon as the trunk is connected to the line wires, wire 39, p^0 , O^{10} 105 to ground, thus keeping the solenoid energized and the core with its insulated end P^{10} inserted in the jack. The relay S^2 becoming energized closes the circuit of the lamp m by the following path: battery B, 110, 101, m to ground. The operator notices the line lamp glowing and inserts the plug P in the jack J in the usual manner. This insertion disconnects the relays S and S^2 from the trunk wires 15, 16, respectively, by 110 breaking the contacts j , j' , and j' , j^4 . The winding O^{10} of the solenoid is now supplied with battery by the following path: battery B, 7, contacts s^2 of the relay S^3 , which is now 115 energized, having its winding in series with the cut-off relay N , 28, p^2 , j^2 , 39, p^0 , O^{10} to ground. 120 It will be observed upon tracing the foregoing circuits that when the operator inserts the plug and puts battery through the conductors 15 and 16 to line this battery is reversed in direction from that normally on the line. Hence the polarized magnet Q' at the substation will reverse its armature from the position shown, raising the target 130

and indicating to the subscriber that his call is answered and switches placed at his command. He then proceeds to manipulate the key K so as to connect himself with the line wanted.

I preferably provide a sufficient number of primary selectors for each group of lines so that each line may have at least ten multiple-contacts on each of the sets p^{25} , p' . 10 These contacts are either identical in every switch as to their angular position (in which case the wipers p^o , p^s , must be displaced one step in each succeeding switch), or the contacts of the same line may be 15 placed and set in each succeeding switch, and the wipers in all the switches of a set may then have the same angular position with relation to the shaft p' .

Assume that subscriber A desires to converse with subscriber No. 2468. He first taps the key K twice each time breaking the circuit and quickly making it again. He then permits a short interval to elapse. The first short break causes the relay S' in 25 Fig. 1 to let go its armature, whereby for a brief instance current is transmitted over the following circuit: B, 7, 30, s^2 , 29, 28, s^3 , 31, 32, D, 23, and ground. At the same time current is sent over a second branch from 30 the wire 31 by way of 33, d^o , d^s and 35 to the wire 21. This is the vertical side of line, and the pulse of current proceeds to the first selector switch in Fig. 2, which will be referred to presently. That portion of the 35 current which reaches solenoid D causes it to pull up quickly, closing the springs d , d' together in passing, but it should be noted that while this closes the circuit 37, 38, it does not produce any effect because battery 40 is disconnected from the wire 26 and hence from the wire 24, because at the instant the solenoid pulls up the armature s^3 of the relay S' is back. It is true that this also takes current off the solenoid D' , but the 45 break is very short, and while either solenoid will pull up on a momentary impulse, neither of them will fall back far enough to perform any work, except on a long change in current. Hence the solenoid D' is unaffected by the short number impulses coming over the line. Both solenoids now have their cores attracted, and so long as the subscriber is sending short breaks, thereby 50 oscillating the armature s^3 back and forth, just so long will both solenoids hold up. Each closure of the armature s^3 , on its back contact, sends a pulse of current to the wire 21 by the path already traced, so that in calling 2468 two breaks being made, two 55 pulses of currents will be sent, and then as the subscriber leaves his line circuit closed, the relay S' will continue to hold up, and the solenoid D, being deprived of current for a considerable period, will let its core 60 retract far enough to close the springs d , d' , 65

and send a single pulse of current to the wire 22 by the following path: B, 7, 30, s^2 , 29, 28, s^3 , 26, 24, 38, d' , d , 37 and 22. The wire 22 is the so-called rotary wire of the first selector switch in Fig. 2. Thus two 70 short breaks produced in the metallic circuit have been translated into two current impulses on the vertical side 21, and one impulse following the group, on the rotary side 22. In a similar manner the next 75 number, 4, is transmitted by making four short breaks at the key K, which are translated into four impulses on the vertical side 21, followed by one impulse on the rotary side 22. Each succeeding group of short 80 breaks is translated in the same way, all that the subscriber has to do to send the number I have mentioned being to tap the key twice, then four times, then six times, and finally eight times, leaving a reasonable 85 interval between the groups. Here the peculiar features of my invention end.

So far as the present application is concerned, any desired form and arrangement of switches and circuits may be adopted, 90 and it will be found that my solenoids and relay scheme of Fig. 1 will enable any standard switches to be worked merely by the subscriber making and breaking the metallic circuit. I emphasize this because 95 it is exceedingly important for two reasons: In the first place it is undesirable and is now considered bad practice to have any grounds on the lines if they can be avoided: and in the second place I am enabled to apply my 100 present invention to existing common battery systems having metallic circuits by merely supplying a separate box or casing with the circuit breaker K of any desired type and the signal device Q'. To connect this for operation requires merely that its binding-posts shall be interpolated in the talking circuit.

I have shown how by tapping his key the subscriber sends successive groups of impulses over the wire 21, and a single impulse at the end of each group over wire 22. This is all it is necessary to assume or to remember in order to understand Fig. 2. The first two impulses come over the wire 21 and cause the relay V to pull up twice, each time closing the following circuit: battery B, 7, 55, 57, V', 56, contacts of magnet T^o , 59, v , g , 60, and ground back to battery. This causes the magnet V' to step up the 115 spindle f two steps, so as to bring the contact wipers w , w^2 and w^o opposite the second rows of contacts. In these rows are the terminals of trunks 210, 220 and test contacts w^{10} of trunk conductor 60, leading to 120 ten second selector switches of the order of 2000. Following the group of two impulses over wire 21, comes the single impulse from wire 22. This energizes rotary magnet R, which pulls up and closes the following cir- 130

cuit: battery B, 7, 55, T° , r , g , 60 and ground back to battery. The magnet T° thereupon pulls up, breaking the circuit 56-59 of the vertical magnet V' , and making the first movement of the escapement so that upon the retraction of the armature t , the side switch arms 46, 47, 48 and 49 are permitted to move one step, whereupon the following circuit is immediately closed for 10 the rotary magnet R' : battery B, 7, 55, 57, R' , 58, 46, 43 and ground back to battery. The rotary magnet R' thereupon pulls up, its stud, r' , breaks the circuit and it lets go, the stud closes the circuit and it pulls up 15 again, and so on with the following results: Each time the armature of the rotary magnet pulls up, it steps around the spindle f one step, and causes each wiper to pass from one contact to the next, making contact with 20 the succeeding one, however, before it leaves the preceding one. At each movement of the armature of the rotary relay, the armature t of the relay T° is kicked up by the stud r^{10} , but released when the wipers 25 come on a fresh contact. That is to say, on the forward stroke the armature t is forced to take the first step toward removing the escapement to release the side switch-arms for their last step. Now as the wiper w° 30 passes over the successive contacts w^{10} of the different trunks all leading to second selectors numbered 2000, it is hunting for an idle one, and the idea is to have the side switch move a second step when an idle 35 trunk is found. Each contact that is busy has a ground on it, as will presently appear. Hence, if in its first movement the wiper w° finds such a grounded contact, it will at once close the following circuit: battery B, 7, 55, 40 T° , 52, 49, T , 50, w° , w^{10} , and ground back to battery. As stated, on the first part of the stroke the armature t is mechanically held up. Current flowing in the circuit I have traced holds it up in the second part 45 of the stroke of the rotary armature, so that after the armature t is once kicked up, it stays up, held alternately by the stud r^{10} and by its own magnet T° , until an idle or ungrounded contact w^{10} is reached. When 50 this happens the armature t falls back, and its escapement permits the four switches 46, 47, 48 and 49 to take their last step. Switch 46 cuts off the rotary magnet and stops the machine instantly. 47 and 48 cut 55 off the vertical and rotary relays V and R , and complete the talking circuit: 21-44, 22-45. 49 cuts off the magnet T° , and closes the circuit of magnet T through wire 51 to ground, thus putting a ground on the 60 wiper w° and all the multiples w^{10} of the contact on which it rests, rendering the trunk "busy," so that no other switch can get in. It is proper to say that the magnet T will not work on the test current through 65 any relay T° . We now have at the end of

the first group of two impulses, the wires 21 and 22 extended respectively as follows: 21, 47, 44, w , w' , 210, 470, V^2 and ground; 22, 48, 45, w^2 , w^3 , 220, 480, R^2 and ground. In other words, the circuit has been extended 70 into the second selector switch F' and the relays V^2 and R^2 have been substituted for those of the first selector. We now have the second group of four impulses coming over the combined wires 21 and 210, followed by 75 a single impulse over the combined wires 22 and 220. The operation of the relays and other parts is precisely the same in this switch as it was in the first selector, the only differences being in matters of release, 80 etc., which will be touched upon later. The net result of the operation of this switch is to pick out an idle connector switch F^2 , and prolong the circuits as follows: 21-210-61; and 22-220-62. The relays V^2 , R^2 of the 85 second selector are cut off, and the relays V^4 , R^4 , are substituted therefor, their connections 63 and 64 being permanent, for these two relays are used in releasing the set of switches as well as in selecting. 90

The subscriber now sends six impulses to relay V^4 , each of which causes the same to pull up, operating the vertical magnet V^5 over the following circuit: battery, 7, 74, V^5 , 80, 67, 78, contacts of relay T^3 , v , 60 and 95 ground back to battery. The number of the wanted line is 68, so that the six impulses working in this way through magnet V^5 step up the spindle f to the sixth row of line-contacts. The subscriber then sends a 100 single impulse over the wire 62 to the rotary relay R^4 which pulls up and closes the following circuit: battery B, 7, 75, 77, T^3 , r , 60 and ground back to battery. The magnet T^3 pulls up and then lets go, it being 105 observed that there is no rotary kicker to hold it up in this case. The side-switch-arms 67, 68, 69 and 70 are therefore stepped around promptly one step. Vertical magnet V^5 is thereby cut out and rotary magnet 110 R^5 cut in, but this magnet has no vibrator, being constructed to turn the switch spindle only one step at a time. The subscriber now sends his final number 8 over the wire 61, and the same relay V^4 responds, each 115 time closing the following circuit: battery B, 7, 74, R^5 , 79, 67, 78, contacts of relay T^3 , v , 60 and ground back to battery. The spindle is therefore stepped around until the wipers w^8 , w^9 rest upon the contacts belonging to 120 line 68 in that hundred. A single impulse now comes over the rotary side of line, and pulls up the relay R^4 , which closes the following circuit, for testing to ascertain if the line wanted is busy: 75, 77, magnet T^3 , 125 r , 60 and ground back to battery. The relay T^3 thereupon pulls up, closing the following circuit: battery B, 7, 75, release relay U^2 , 76, contacts of relay T^3 , 82, 70 (this being on its second point), w^8 , and to the tip. 130

side of the line being tested. Now, if the line wanted, is already connected either through a connector switch, such as shown in Fig. 2, or through a primary selector switch, such as shown in Fig. 1, there will be a ground on the tip side, otherwise not. In the first case, the ground will be through the wire 71, switch-arm 68, wire 65 and magnet X. In the other case it will be through the wire 3, the wiper p^4 , the wire 15, and the relay S'. In either case, if the line is busy the energization of the release relay U² causes the release magnet U³ of the testing switch to pull up thereby releasing the switch and causing it to return to zero position. In other words, the subscriber does not get on to the line wanted if it is busy. If the line wanted is not busy, the momentary impulse over the rotary side ceases, the relays R⁴, T³ let go, and the side switches go the last step, cutting off the working magnets R⁵, V⁶ entirely, substituting the ringing relay Z through the wire 81 and the arm 67, and completing the circuit of wires 65 and 66 through 71 and 72 to the line wanted. In order to ring the wanted subscriber, the next thing is to energize the relay Z, which is ordinarily done by simply breaking the circuit at the calling subscriber's station by means of a push-button. In the present system we cannot do this because a prolonged break would deenergize the solenoid D', and would release all the switches. So I do not provide any special ringing button, but after the line wanted is selected, a succession of taps on the key K is produced by the calling subscriber, and these energize the relay Z, by energizing the relay V⁴. I preferably make the relay Z a solenoid like those shown in Fig. 1, so that the succession of short closures will hold its core up as long as they continue. The energization of this relay opens the springs z, z', z², z⁴, and closes z' on z² and z⁴ on z⁵, thus connecting the ringing generator G across the wipers w⁸, w⁹. When the called subscriber answers, he derives current for his transmitter from the main battery through the bridging coils X and X'.

When the subscribers have finished talking, or in the event that the caller finds the wanted one busy, the receivers are hung up, the metallic circuits being thus opened at the substations. Referring to Fig. 1, it will be observed that this opening at substation A lets go the relay S', which cuts off the solenoid D', whose core d¹¹ drops to its normal position shown in the drawing. The springs d⁷, d⁸ and d⁹ therefore come together, and battery is put on both trunk-wires 21 and 22, by the following path: B, 7, 30, s², 29, 34, d⁹, d⁸, and d⁷, through wires 36 and 35. Referring to Fig. 2, these simultaneous impulses over both trunk-wires 61 and 62 energize both relays V⁴ and R⁴ at the

same time, closing together the springs v⁸ and v⁹, and the following release circuit: battery, 7, 75, U², 76, r⁸, v⁸, w⁵⁰, w⁴⁰, T', 490, ground back to battery. Magnet U² releases and restores the connector switch F²; 70 relay T' closes the following release circuit: B, U', contacts of T', 60, w¹⁰, w⁰, 50, T, 49, 51 and ground back to battery. Magnet U' thereupon releases and restores the switch F'. All the automatic switches are therefore restored. The de-energization of the relay S' also closes the 80 circuit of the supervisory lamp s', causing it to glow. The operator perceiving this disconnect signal withdraws the plug P from the jack J, opening the circuit of the winding O¹⁰, allowing the plunger or core to 85 spring back and the insulated portion P¹⁰ to leave the jack, whereupon the solenoid begins to rotate in the usual manner and the subscriber is free to make another call at any time. 90

Having thus described my invention, what I claim and desire to secure by Letters Patent is:—

1. In a telephone exchange system a plurality of subscribers' lines, a number of answering jacks less than the number of lines, an automatic switch adapted to connect a calling line with an idle answering jack, an answering plug adapted to coöperate with said jack, an automatic switch for selecting 95 and connecting with a wanted line, a trunk directly connected to and terminating in said plug at one end and similarly connected to and terminating in said automatic switch at the other, said automatic selector 100 switch being fixedly and permanently connected with said answering plug, and means to actuate said switch to select a wanted line, substantially as described.

2. In a telephone exchange system a plurality of subscribers' lines, a number of answering jacks less than the number of lines, an automatic switch adapted to connect a calling line with an idle answering jack, a cord-circuit terminating at one end in an 110 answering plug, and at the other end in an automatic selector switch, and means to actuate said switch to select a wanted line, said means being controlled by the calling subscribers, substantially as described. 115

3. In a telephone exchange system a plurality of line-circuits, and means for interconnecting them comprising the following instrumentalities: primary switching mechanism for answering calls, an answering 125 jack connected thereby to a calling line, a calling signal associated with said jack and becoming energized when the same is so connected, an answering plug adapted to connect the jack with a cord-circuit and by its 130

insertion in the jack to restore or retire the call signal, a supervisory signal associated with said answering plug, an automatic selector switch for selecting and connecting 5 with a wanted line, a trunk directly connected to and terminating in said plug at one end and similarly connected to and terminating in said automatic switch at the other, and means to actuate said selector 10 switch, substantially as described.

4. In a telephone exchange system, a plurality of line-circuits, and means for interconnecting them comprising the following instrumentalities: primary switching mechanism for answering calls, an answering jack connected thereby to a calling line, a call signal associated with said jack and becoming energized when the same is so connected, an answering plug adapted to connect the 20 jack with a cord-circuit and by its insertion in the jack to restore or retire the call signal, a supervisory signal associated with said answering plug, an automatic selector switch for selecting and connecting with a wanted 25 line, a trunk directly connected to and terminating in said plug at one end and similarly connected to and terminating in said automatic switch at the other, means to actuate the selector switch and means for re- 30 storing or releasing the same, substantially as described.

5. In a telephone exchange system a plurality of line-circuits, and means for interconnecting them comprising the following 35 instrumentalities: primary switching mechanism for answering calls, an answering jack connected thereby to a calling line, a call signal associated with said jack and becoming energized when the same is so connected, an answering plug adapted to connect the jack with a cord-circuit and by its insertion in the jack to restore or retire the call signal, a supervisory signal associated with said answering plug, an automatic 40 selector switch adapted to connect the cord-circuits with a wanted line, means at the subscriber's station for actuating the selector switch, and means controlled by the subscriber for releasing or restoring the same, 45 substantially as described.

6. In a telephone exchange system a plurality of line-circuits and means for interconnecting them, comprising the following instrumentalities: a number of answering 55 jacks less than the number of lines, an automatic switching device for connecting a calling line with an idle answering-jack, a cord-circuit terminating at one end in an answering plug to coöperate with said jacks, 60 and at the other end in a system of automatic selector and connector switches for selecting wanted lines, together with controlling means for said automatic switching device between the lines, and answering- 65 jack, initially controlled by the calling sub-

scriber, but controlled during connection through the jack and plug and thence through the cord-circuit, whereby a calling line will remain connected with its answering-jack until the answering-plug is finally 70 withdrawn therefrom, substantially as described.

7. In a telephone exchange system a plurality of line-circuits, each having a cut-off relay, a line-signal relay, and answering and 75 connecting terminals, the former in the banks of contacts of primary selector switching means, and the latter in the banks of automatic selector switches, a number of answering-jacks less than the number of 80 lines, each jack connected to a primary switching device, and adapted thereby to be connected to calling lines, calling signals associated with the answering jacks, means associated with the line-relays to initially control the primary switching devices, means to energize each calling signal when a line is connected to its associated jack, answering plugs having cord-circuits connected to the 85 automatic selector switches, means associated with each answering-plug to control the primary switching device and maintain it in connection with the calling line while the plug is in the jack, means operated by the plug to restore the calling signal, and a 90 supervisory signal associated with the plug circuit, substantially as described.

8. In a telephone exchange system a plurality of line-circuits, each having a cut-off relay, a line-signal relay, and answering and 100 connecting terminals, the former in the banks of contacts of primary selector-switching means, and the latter in the banks of automatic selector switches, a number of answering-jacks less than the number of 105 lines, each contact connected to a primary switching device, and adapted thereby to be connected to calling lines, calling signals associated with the answering-jacks, means associated with the line-relays initially controlling the primary switching devices, means to energize each calling signal when a line is connected to its associated jack, answering plugs having cord-circuits connected to the automatic selector switches, means 110 associated with each answering plug to control the primary switching device and maintain it in connection with the calling line while the plug is in the jack, means operated by the plug to restore the calling signal, and a 115 supervisory signal associated with the plug circuit, together with means controlled by a calling subscriber for actuating and releasing the automatic selector switches, substantially as described.

9. In a telephone exchange system, a plurality of subscribers' lines and substations provided with sending devices, answering jacks less in number than the number of lines, and means including terminal plugs 130

and automatic switches controlled by said sending devices for effecting connection between the answering jacks and any wanted subscribers' lines, substantially as described.

5 10. In a telephone exchange system, a plurality of subscribers' lines and substations provided with sending devices, a number of answering jacks therefor less than the total number of lines, automatic switching devices 10 adapted to connect the subscribers' lines, when calling, to the answering jacks, terminal plugs and automatic switches controlled by said sending devices for effecting connection with other lines, substantially as 15 described.

11. In a telephone exchange system, a plurality of subscribers' lines and substations provided with sending devices, a number of answering jacks therefor less than the total 20 number of lines, means to connect a calling line with an idle jack, and means including terminal plugs and automatic switches controlled by said sending devices for connecting said jack with the line wanted.

25 12. In a telephone exchange system, a plurality of subscribers' lines and substations provided with sending devices, a number of answering jacks less in number than the number of lines, automatic switching devices 30 adapted to connect each calling line with an idle jack and means including a terminal plug and automatic switches controlled by said sending device for connecting said jack with the lines wanted, substantially as 35 described.

13. In a telephone exchange system, a plurality of subscribers' lines and substations provided with sending devices, a number of answering terminals therefor less than the 40 number of lines, a calling signal associated with each terminal, means to connect a call-

ing line with an answering terminal, means thereupon becoming active to operate said signal together with automatic switches responsive to said sending devices for effecting 45 the connection of a calling and a called line.

14. In a telephone exchange system, a plurality of subscribers' lines and substations provided with sending devices, a number of answering spring jacks therefor less than 50 the number of lines, a calling signal associated with each spring jack, means to connect a calling line with an answering jack, means thereupon becoming active to operate said signal, together with means including a 55 terminal plug and automatic switches controlled by said sending device, for connecting the spring jack with the wanted line, whereby the calling signal may be restored or retired, substantially as described. 60

15. In a telephone exchange system, a plurality of subscribers' lines and substations provided with sending devices, answering jacks less in number than the number of lines, automatic means for selectively effecting connection between an answering jack and a calling line, automatic means for effecting a connection with a wanted line, an operator's manual means for effecting connection between an answering jack and the 70 line connecting means, means for restoring said line connecting means controlled by the calling subscriber and means for restoring the said line selective means controlled by the operator. 75

In testimony whereof I affix my signature in presence of two witnesses.
